A. G. MACKEY

MATCH BOX ATTACHMENT

Filed May 29, 1922

Inventor

Albert G. Mackey,

By *Albert G. Mackey*

Attorney

UNITED STATES PATENT OFFICE.

ALBERT G. MACKEY, OF WASHINGTON, DISTRICT OF COLUMBIA, ASSIGNOR TO THE AUTOMAC COMPANY, A CORPORATION OF DELAWARE.

MATCH-BOX ATTACHMENT.

Application filed May 29, 1922. Serial No. 564,378.

To all whom it may concern:

Be it known that I, ALBERT G. MACKEY, citizen of the United States, residing at Washington, in the District of Columbia, have invented certain new and useful Improvements in Match-Box Attachments, of which the following is a specification.

This invention relates to certain new and useful improvements in match box attachments and pertains more especially to attachments of this type used in connection with memorandum holders of the general character disclosed in my application for patent filed February 28, 1922, Serial No. 15 539,842.

The primary object of the invention is to provide an attachment which is secured in position on the table so as to cause the box of matches to be normally concealed and protected by the table, and which also allows the slide containing the matches to be easily and quickly moved to a position projecting out from an edge of the table to allow of removal of the matches.

A further object of the invention is to provide an attachment which is secured to the table by the arm of the clamp, so as to thereby eliminate the necessity of the use of separate fastening means therefor.

A still further object of the invention is to provide means, formed on the table which acts to assist in securing the box in position and which also acts to prevent accidental movement of the slide out of the box.

The invention also aims to provide an attachment of simple and economical construction and has still further and other objects which will be later set forth and manifested in the course of the following description.

In the drawings:

Figure 1, is a rear elevation;

Figure 2, is a section on line 2—2 of Figure 1;

Figure 3, is a section on line 3—3 of Figure 1, and

Figure 4, is a detail view of the holder in detached position.

In proceeding in accordance with the present invention the table 1, has a suitable spring clamp 2 employed for securing a pad or card thereon and further has a clamp 3 for attachment to the steering column or standard of an automobile or to the col-

umn of a telephone. As disclosed in my 55 said application, the arm 4 of the clamp is secured to the back of the table by means of rivets, or other suitable fastenings 5, and the present invention proposes to utilize the arm and its securing means for fastening the 60 match box holder in position. Accordingly the holder is formed of a strip or section of sheet metal having a body 6 of substantially 65 U-shape, one of the sides of the body being laterally extended to form an attaching wing 7 which is interposed between the arm 4 and the rear face of the table, the wing being penetrated by the fastening rivet 5 which secures the arm to the table.

The body 6 is shaped to receive the commercial size of safety match box B and holds the latter against the under face of the table adjacent the outer end of the latter and also against the curved or rounded edge 9 of the table. Inward movement of 70 the box and slide is limited by a stop lug 10 which is formed integral with the inner end of the body, while accidental outward movement of the slide S is prevented by the curved or rounded edge 11 on the outer end 75 of the table, the latter edge having but sufficient engagement with the outer end of the slide S so as to allow the outer end of the latter to be sprung over the edge 11 and thereby moved into and out of the box by 80 the expenditure of but slight force.

The box B is preferably held with the match igniting surface substantially flush with the lower marginal edge of the table so as to allow of convenient scratching of the 90 matches thereon, and to also allow the slide to be moved, by pressing against the inner end thereof, to cause the outer end to project outwardly beyond the outer end of the table to permit of ready removal of the matches.

From the foregoing it will be seen that the table protects the box and its contents and that the box is effectively held in position and the slide held against accidental movement, while still permitting movement 95 thereof to allow of extraction of the matches. The arm 4 abuts the adjacent side wall of the body and accordingly acts to brace same and to prevent lateral movement thereof.

The invention while illustrated in connection with a match box, is not so limited, since obviously the body 6 can be shaped and used for various purposes, such as a

cigar or cigarette holder, or for holding other articles of different types.

What is claimed is:

1. In combination with a support having a flanged side and end edge, and attaching means for the support including an arm, a match box holder including a body of substantially U-shape having a lateral wing extending from its inner side and interposed between the arm and the support, fastening means for the arm extending through the wing to secure both the arm and wing to the support, the body being disposed to have its outer side substantially alined with the flanged side edge of the support to cause the box to be engaged by said flanged side edge of the support and to cause the outer end of the slide to be engaged by the flanged end edge of the support, and a stop on the inner end 20 of the body to engage the box and slide.
2. In combination with a support and attaching means therefor, a match box holder including a body of approximately U-shape having a lateral wing extending from its inner side and interposed between the attaching means and the support, and fastening means for the holder extending through the wing, the attaching means and the support, the holder having its top confronting the under side of the support so as to hold the box between the holder and the support and to allow the slide of the box to be moved to project outwardly from a marginal edge of the support.
3. In combination with a support having a flanged edge, a match box holder, and means to secure the holder to the support so as to cause an end of the slide of the match box to be engaged with said flange edge.
4. In combination with a support having a flanged edge, a substantially U-shaped match box holder disposed to cause an end of the slide of the match box to be engaged 45 with said flanged edge, and means to secure the holder to the support so as to hold the

match box between the holder and the adjacent face of the support.

5. In combination with a support having a flanged edge, U-shaped holder having a wing on one side thereof secured to the support and having its opposite side alined with the flanged edge so as to hold the match box between the holder and the adjacent face of the support and with the outer side of the match box engaged with the flanged edge.

6. In combination with a support having angularly related flanged edges, a match box holder, and means to secure the holder to the support so as to hold the outer side of the match box engaged with one of the flanged edges and an end of the slide engaged with the other of the flanged edges.

7. In combination with a support having an attaching member, a holder of approximately U-shape having its top confronting the support so as to hold a match box between the support and the holder, one side of the holder having a wing engaged between the support and the attaching member.

8. In combination with a support, a match box holder having a stop on one end and having its opposite end open, means to attach the holder to the support and therebeneath and with a side of the box arranged adjacent a marginal edge of the support whereby an end of the slide may be moved to project outwardly from the support, and means to engage the said end of the slide to hold the latter against accidental movement and still permit movement of the slide into and out of match extracting position.

9. In combination with a support and an attaching arm therefor, an article holder having article holding means and having a member interposed between the arm and the support, and fastening means passed through the support, the arm and said member for securing all of the parts together.

In testimony whereof I affix my signature.
ALBERT G. MACKEY.
